Patented Jan. 15, 1929.

UNITED STATES PATENT OFFICE.

ROY H. SMITH, OF KENT, OHIO.

QUENCHING APPARATUS.

Application filed May 8, 1925. Serial No. 28,846.

The present invention relates to apparatus which is particularly designed for use in connection with quenching of ferrous articles after they have been heated.

5 The apparatus is particularly designed for quenching small articles which are delivered to the apparatus continuously or intermittently, and are received and discharged by the quenching apparatus as a substantially

10 continuous process.

The apparatus is particularly designed to rapidly quench ferrous articles, in fact, to accomplish the quenching as near instantaneously as this can be done, and in addition 15 the apparatus is so designed that the quenching fluid delivered thereto will by the mechanical impact between the ferrous articles and the quenching liquid, cause a tossing about of the ferrous articles within the

20 quenching fluid.

Reference should be had to the accompanying drawings forming a part of this specification, in which Fig. 1 is a side elevation with portions in section showing the apparatus of the present invention in co-operation 25 with apparatus for heat treating ferrous articles. Fig. 2 is an end elevation with portions in section of the showing in Fig. 1; Fig. 3 is a section substantially upon the line

30 3—3 of Fig. 2.

The quenching apparatus comprises an outer casing member 1 within which and spaced from the side walls thereof is an inside member 2. This construction provides an annular space 3 which surrounds the inside member 2. There is a pipe 4 which connects with the space 3 being threaded into a suitable opening formed in the outside casing member 1, and water may be delivered through pipe 4 to the space 3.

40 For convenience in manufacture the inside member 2 is so designed that it may be separately made and assembled with respect to the outside casing 1, but of course, this is an unessential detail. The member 2 is provided at its upper end with a bell-shaped mouth piece 5 which is adapted to receive and guide ferrous articles to be quenched, to which more complete reference will later be made. The bell member 5 is supported from the member 2 by means of ribs 6 so that at the top or upper end of the member 2 there are a series of openings 7. In fact, the top of the member 2 is entirely open except for the space which is occupied by the ribs 6.

The member 2 has a plurality of rows of

holes extending through the side wall, as indicated at 8. These holes are preferably slanting and are so arranged that streams of water discharged from them will be converging. There are a large number of these openings or holes 8 so that quenching fluid which is discharged into the chamber 3 through the pipe 4 will readily pass through these openings and under the pressure which is existent in the fluid coming through the pipe 4. The water which is discharged into the interior of the member 2 will overflow the top and the proportion of the parts is such that there will be a free and ready movement of the quenching fluid within the member 2 and discharging through the top thereof.

The object of the construction is to pass a very large quantity of quenching fluid 75 through the member 2 and discharge the same in a short space of time.

It will be readily seen that the discharge of a large number of jets of water into the body of water that fills the interior of the member 2 will cause a great turbulence in that water. This is purposeful so that the articles discharged into the member 2 will be more or less tossed about and moved around within the quenching fluid as these articles are delivered into the member 2.

The bottom portion of the casing 1 has an opening 9 through it which communicates with the interior of the member 2. This opening is closed by a closure member 10 which is carried by arms 11 which arms are secured to a short shaft 12 which is supported in ears 13 carried by the body portion 1.

A lever 14 is also secured to the shaft 12 at the central portion thereof so that as the lever 14 is operated the closure member 10 may be moved to open or closed position. Obviously the operation of the closure member 10 will enable the discharge of the material which is delivered to the quenching apparatus.

Connected with the chamber 3 are pipes 15 and 16, these pipes extending from the bottom or lower portion of the outside body portion 1. The pipes 15 and 16 are connected by suitable piping as indicated at 17, and in substantially the central portion of the connecting pipes 17 there is a nozzle 18 which discharges upwardly and against the lower portion of the closure member 10.

110 This nozzle member will normally play against the under side of the closure member

10 so as to keep this cool at all times and assist in conduction of heat of any ferrous articles which may by chance fall and rest upon the top of the closure member 10.

- 5 It will be desirable to refer to the heat treating apparatus which may be used in connection with the quenching apparatus described because in the association of the quenching apparatus with the heat treating apparatus, it 10 is possible to operate the lower closure member for the quenching apparatus so that it may be intermittently and automatically operated to discharge ferrous articles which it has received from the heat treating apparatus.

The heat treating apparatus herein disclosed comprises outside cylindrical body member 20 which is suitably lined and has a central chamber 21. Extending through the 20 central chamber is a cylindrical member 22 which is so mounted at opposite ends that it may rotate. Within the member 22 is a spiral member 23 which is utilized to feed ferrous articles delivered at one end of the heat 25 treating apparatus so that they progress through the tubular member 22 and may be discharged through openings 24 which are at the end of the heat treating apparatus, as shown in Fig. 1.

- 30 It will be understood that suitable heating means is applied to the cylindrical member 22.

The ferrous articles as they are discharged through the openings 24 fall through an 35 opening 25 which is formed in the outside casing 20 of the heat treating apparatus, and are guided by a chute or spout 26 into the bell-shaped portion 5 of the quenching apparatus.

- 40 In the present instance the shaft 27 which

extends from the end of the cylindrical member 22 has a cam 28 at the end thereof.

Mounted upon the casing 20 is an arm 29 which is pivotally secured at 30. This arm 29 has a wheel member 31 at the end thereof 45 which is in contact with the cam 28.

The lever 29 is a bell crank lever, the other arm of which is 29^a, and the arm 29^a connects by means of a long lever 32 with the arm 14 which as before stated will cause movement of 50 the bottom closure member 10.

It will be perfectly obvious that the cam 28 will periodically move the lever 29 and the other levers connected therewith so as to cause the bottom member 10 to open, and subsequently to close.

It will be seen that by the provision of a suitable cam 28 the time that the closure member 10 remains closed and the time that it remains open can be accurately defined so 60 that just the desired period of quenching can be given to the ferrous articles.

Having described my invention, I claim:

1. A quenching receptacle having a portion 65 for the reception of articles, a side wall provided with a large number of fluid inlets and connected at points to said portion, a header compartment surrounding said side wall, means for introducing fluid into said header compartment and subsequently into the 70 receptacle, said fluid being permitted to pass off at the upper portion of the receptacle.

2. A quenching receptacle having an open top, a movable closure for the bottom of the receptacle, and means for introducing a multiplicity of streams of fluid through the side 75 wall of the receptacle.

In testimony whereof, I hereunto affix my signature.

ROY H. SMITH.
